UNITED STATES PATENT OFFICE.

EDWARD V. PECHIN, OF PHILADELPHIA, PENNSYLVANIA, ASSIGNOR TO
THE H. K. MULFORD COMPANY, OF SAME PLACE.

TABLET-MACHINE.

SPECIFICATION forming part of Letters Patent No. 668,016, dated February 12, 1901.

Application filed November 30, 1900. Serial No. 38,216. (No model.)

To all whom it may concern:

Be it known that I, EDWARD V. PECHIN, a citizen of the United States, residing in Philadelphia, Pennsylvania, have invented certain

5 Improvements in Tablet-Machines, of which the following is a specification.

My invention relates to certain improvements in tablet-making machines, and in particular to improvements in the plunger-heads
10 of machines of the type covered by my application for patent, Serial No. 739,537, allowed July 24, 1900.

The object of my invention is to so construct the plunger-heads on machines of this class
15 that it shall be possible to use one or more punches for forming tablets by but a slight change in the mechanism involved. Formerly when it was desired to adjust a machine to form three tablets, for instance, instead of
20 two at one stroke it was necessary to replace both the upper and lower plunger-heads which held but two punches by others having the required number of punches. By my invention I am enabled to use but one set of
25 plunger-heads, while being able to adjust the machine to form any practical number of tablets at one stroke. This object I attain in the following manner, reference being had to the accompanying drawings, in which—

30 Figure 1 is a sectional view of sufficient of a tablet-making machine to show the construction and use of my improved plunger-head. Fig. 2 is an inverted plan view of the upper plunger, showing two punches held in place
35 by my device; and Fig. 3 is a plan view of the lower plunger-head, showing the two ejectors.

Referring to Fig. 1, A is part of the frame of the machine, having a table A², in which is the die h, having orifices in which the tablets are formed. The plunger B is mounted
40 in guides A' on the frame and is reciprocated toward and from the table A².

F is a plunger-head screwed into the plunger B and preferably held in place by a set-screw n'. This head consists of the threaded portion n, having an extension n², on which the cap m fits tightly. This cap has an internal flange at its outer end. An end piece g' is mounted in the cap and is held in place by

said flange. The end piece has two or more 50 holes through which headed punches f' f' project, the heads of the punches being confined between the end piece and a block e'. This block has a rounded upper surface resting against the end of the extension n². 55

C is the lower plunger, carrying the lower plunger-head D, which in the present instance is screwed into it. This head consists of the supporting-piece d', having a head d², an end piece g, and the flanged cap d, said cap being 60 screwed onto the head d², as shown in Fig. 1. Within the cap is a block e, rounded on its under side and supporting the ejectors f f, which pass through the end piece g. The heads of the ejectors are confined between 65 the block e and the end piece. The head D operates in the cavity G of the table A². The ejectors extend into the orifices in the die h, forming the bottom of the die. The plate k is the die-filling plate and has a passage connected to a hopper, neither of the latter being shown, said hopper supplying material to be made into tablets. The plate is reciprocated and agitated over the die by appropriate mechanism, allowing the material to pack 70 evenly in the die and then returning, so as to permit the plungers to compress the material. As the plate moves away from the die the upper plunger compresses the material therein and the lower plunger is raised so as 75 to eject the compressed tablet.

The end pieces g and g' are preferably circular in outline and have the holes for two or more punches or ejectors arranged as shown in Figs. 2 and 3. 85

It will be understood by those skilled in the art that it is often desired to vary the number of tablets formed at one stroke of the machine, and in order to do this it was formerly necessary to replace the caps d and m 90 by others having a number of holes corresponding to the number of punches used, besides inserting said punches and the proper die. By my invention it is not necessary to carry a stock of caps having different numbers of holes for each number of punches used in the machine, a set of removable plates g and g', having various numbers of aper-

tures, being used instead, with but one set of caps for the plunger-heads in which said end plates or pieces can be inserted.

I claim as my invention—

- 5 1. In a plunger-head for a tablet-making machine, the combination of a body portion constructed to be attached to a plunger, a cap on said body portion, an end piece held in said cap and having holes therein and 10 punches projecting through said holes, substantially as described.
- 15 2. In a plunger-head for a tablet-making machine, the combination of a body portion constructed to be attached to a plunger, a cap on said body portion having an inwardly-projecting flange at the end, an end piece held in said cap by said flange, having one or more holes therein and one or more punches 20 projecting through said holes, substantially as described.

3. The combination in a plunger-head for a tablet-making machine, of a body portion screwed into a plunger and having an extension, a cap fitting on said extension constructed with an inwardly-projecting flange at its 25 end, a removable circular end piece held in said cap by the flange, one or more holes in said end piece, one or more headed punches projecting through said holes and a block between the extension of the body-section and 30 the heads of the punches, substantially as described.

In testimony whereof I have signed my name to this specification in the presence of two subscribing witnesses.

EDWARD V. PECHIN.
